DESIGN FOR A FAN

Anthony J. Bittson, New York, N. Y.

Application March 15, 1940, Serial No. 90,939

Term of patent 7 years

To all whom it may concern:

Be it known that I, Anthony J. Bittson, a citizen of the Republic of France and a resident of New York city, county of New York, and State of New York, have invented a new, original, and ornamental Design for a Fan, of which the following is a specification, reference being had to the accompanying drawing, forming part thereof, wherein the figure is a front elevational view of a fan, showing my new design.

The bottle form shown is flat and in substantially the same plane as the blade element, the three-dimensional appearance being simulated.

I claim:

The ornamental design for a fan, substantially as shown and described.

ANTHONY J. BITTSON.
